(57) **CLAIM**

The ornamental design for a memorial marker, as shown and described.

DESCRIPTION

FIG. 1 is an upper front perspective view of a first embodiment for a memorial marker showing my new design; FIG. 2 is a lower rear perspective view thereof; FIG. 3 is a left side view thereof; FIG. 4 is a front side view thereof; FIG. 5 is a right side view thereof; FIG. 6 is a rear side view thereof; FIG. 7 is a top view thereof; FIG. 8 is a bottom view thereof; FIG. 9 is an upper front perspective view of a second embodiment for a memorial marker showing my new design; FIG. 10 is a lower rear perspective view thereof; FIG. 11 is a left side view thereof; FIG. 12 is a front side view thereof; FIG. 13 is a right side view thereof; FIG. 14 is a rear side view thereof; FIG. 15 is a top view thereof; and, FIG. 16 is a bottom view thereof.

The oblique line shading with greyfill on alternating panels represent that the panels are transparent or translucent. The broken lines immediately adjacent to the shaded regions represent the bounds of the claimed design while all other broken lines represent portions of the memorial marker that form no part of the claimed design.
